UNITED STATES PATENT OFFICE

JOSEPH C. BROOKES, OF CHICAGO, ILLINOIS

HAIR CURLER

Application filed August 26, 1929. Serial No. 388,460.

This invention relates to devices for curling and waving hair and has a special relation to the curler or curling stick upon which the hair is wound.

5 In using curling sticks of this type a clip is usually used for clamping a strand of hair at a point near the scalp, after the free end of the strand is wound upon the middle portion of said stick. Due to the unevenness of 10 the free ends of the strand it has been found that in winding the same about the stick instead of obtaining uniform concentric turns there results turns thicker at one portion of the stick than at the others, thus causing some 15 parts of the strand to be wound tighter than others resulting in loss of efficiency in the curling or waving operation. Also, with the curling sticks heretofore used it has not been possible to provide a permanent wave or curl 20 in a portion of a strand of hair intermediate the free ends thereof and the scalp without necessitating the curling or waving and steaming of the whole length of the said strand, particularly that portion of the strand 25 of hair which still retains a wave.

The main object of this invention is to provide a curler of the character described, which will have means associated therewith for permitting the rewaving of a strand of 30 hair without subjecting that portion of the strand which still retains a wave to wrapping or steaming.

Another object of this invention is to provide a curling stick of the character described 35 which will have means associated therewith for receiving on the inside thereof the free ends of a strand of hair prior to the beginning of the winding of said strand upon said curling stick whereby when the strand is 40 wound on the stick it will lie thereon in uniform concentric turns.

A further object of this invention is to provide a curler of the character described, which is hollow throughout its length and 45 open at one end, and which is provided on the outer surface thereof intermediate the ends thereof with a longitudinally disposing opening, which opening is in communication with the open end of said curler by means of a 50 narrow slit whereby a strand of hair may be

clamped intermediate the ends thereof and said clamp inserted into the hollow tube through its open end with that portion of the strand extending on one side of said clip being disposed within said tube or extending 55 through the open end thereof, and the portion of said strand lying on the other side of said clip extending through said longitudinally disposed opening so that the latter portion may be wound about said tube in the 60 usual manner.

A further object of this invention is to provide a curling stick of the character described comprising a hollow tube having a longitudinally disposed opening on one face thereof, 65 said opening being in communication with one open end of said tube, whereby the free ends of a strand of hair may be disposed within the hollow portion of said stick or may be permitted to extend through the said open 70 end before the remaining portion of said strand is wound on said stick after subjecting that wound up portion to the usual wrapping and steaming process.

A still further object of the invention is to 75 provide a curling stick of the character described which may be easily and economically constructed, and which will be simple in operation and highly efficient in carrying out the purposes for which it is designed. 80

With the foregoing and other objects in view, it will appear as the description proceeds, the invention consists in certain novel features of construction and arrangement of parts, hereinafter more fully described, illustrated in the accompanying drawings and particularly pointed out in the appended claims, it being understood that various changes in the form, proportion, size, and minor details of the structure may be made 85 without departing from the spirit or sacrificing any of the advantages of the invention.

Stated generally, the invention comprises a curling stick formed in the shape of a hollow tube open at one end, the outer surface of 95 which is curved, being of lesser diameter in cross-section at the center than at the outer ends thereof, the cross-sectional diameter increasing gradually to provide the curved surface for the stick. One of the free ends of the 100

curling stick is provided with suitable ratchet openings by means of which it may be detachably secured in the usual manner after the strand of hair has been wound thereon to the clip usually used for clamping the said strand of hair at a point near the scalp. Provided in the outer face of the curling stick is a longitudinally disposed opening extending along a length of about one-half that of the curling stick, said opening being disposed intermediate the ends thereof and is in communication with the open end of said stock opposite from that having the ratchet openings by means of a narrow longitudinal slit provided adjacent the last mentioned free end thereof. In the art of permanent hair waving it is the practice to divide the hair upon the head into a plurality of strands, the size of the strands depending largely upon the tightness of the wave it is desired to produce, and the thickness or fineness of the hair. When the hair has been so divided into strands, each strand is wound tightly upon my improved curler, the latter permitting the rewaving of that portion of the strand of hair disposed immediately adjacent the scalp without subjecting the remaining portion thereof, which still retains a wave to wrapping or steaming. This is accomplished by clamping the strand of hair at the point where the unwaved hair begins with a suitable clip, which clip is adapted to be inserted through the open end of the curler into the hollow portion thereof, the strand of hair passing through the narrow slit and extending through the longitudinal opening provided on the outer surface of the curler. The free end of the strand, or that portion which still retains a wave, will be disposed within the curler or will extend through the open end thereof. The unwaved portion may now be wound upon the stick by turning the same towards the scalp. When that unwaved portion of the strand has been so wound, the same may be subjected to any well known waving and steaming process for imparting to the same a wave or curl, known commercially as a permanent wave. It will thus be noted that only that portion of the strand wound on the curler will thereby be subjected to the wrapping or steaming process and that the remaining portion of the strand which still retains a wave will be free from any such steaming action. Also by having the free and uneven ends of the strand disposed within the hollow portion of the stick, or extending through the open end thereof, it will be noted that that portion of the strand wound on the stick will be formed in uniform and concentric turns.

For the purpose of facilitating an understanding of my invention I have illustrated in the accompanying drawings a preferred embodiment thereof, from an inspection of which, when considered in connection with

the following description, my invention, its mode of construction and many of its advantages should be readily understood and appreciated.

Referring to the drawings in which similar characters of reference are employed to indicate corresponding parts throughout the several figures of the drawings:

Figure 1 is a view in side elevation of a curling stick embodying the present invention;

Figure 2 is a view taken on lines 2—2 of Figure 1;

Figure 3 is a front view of the improved curling stick showing how the winding of the strand thereon is begun;

Figure 4 is a top plan view of my improved curling stick;

Figure 5 is a view taken on lines 5—5 of Figure 4;

Figure 6 is a top plan view of my improved curling stick showing the winding of the strand thereon substantially completed;

Figure 7 is a view of the same taken on lines 7—7 of Figure 3, and

Figure 8 is a view in perspective of a spring clip.

Referring to the drawings more specifically by characters of reference, the reference character 10 designates generally a curling stick the central portion 11 of which is provided with an outer curved surface said surface being of lesser cross-sectional diameter at the center thereof than at the ends. The said stick 10 is hollow throughout its length and is open at the ends thereof. A portion of said stick immediately adjacent one end thereof is provided with a plurality of openings or slits 12 which are adapted for engagement by the sprung clip or tongue provided on the clip (not shown) which is usually used for clamping the strand of hair at a point near the scalp. The oppositely disposed end portion 13 is provided with a longitudinal slit 14, the free end of said slit communicating with its adjacent end of the hollow tube 10, the sides of said slit being curved adjacent the end thereof, as shown at 15, to permit ready access to said slit 14. The other end of said slit 14 is in communication with a longitudinally disposed opening 16 provided in the top surface of the tube 10, said opening being disposed intermediate the ends of said tube and extending substantially along the whole length of the curved surface 11.

Pivotedly mounted at 17, at one end of said tube, is a member 18, said member 18 being adapted to be disposed over the strand of hair when the latter has been wound on the portion 11.

In practice a strand of hair 20 of suitable size at the scalp to cover the greater part of the stick when wound up, has clamped thereon at a point near the point where the old wave stops a suitable clip or pin 19, said pin, together with the hair 21 of the strand 20

clamped therebetween is then inserted through the end of the tube 10 into the hollow portion of said tube, that portion of the strand lying between the scalp and the clip 19 passing through the slit 14 until the same is disposed over the central portion 11, upon which it may be wound.

It will be noted that when in this position the free ends of the strand will be disposed within the tube 10 or will extend from the open end thereof whereas the portion of the strand beyond the clip 19 will extend through the opening 16 and will be arranged substantially about the middle of the portion 11, and in position to be wound on the stick 10. The stick 10 may then be turned toward the scalp in the usual manner thereby winding up the strand upon the central portion 11 thereof.

It will thus be noted that with my improved curling stick the strand of hair may be readily wound up thereon in uniform, concentric turns which will result in uniform curling and stretching of the hair.

It will also be noted that either in waving or re-waving a strand of hair said curling or waving operation may be begun at any point along the strand intermediate the free ends thereof and the scalp. Thus, at a later time after a wave has been placed in a strand of hair, that portion of the strand immediately adjacent the scalp which has grown since the first waving, may be curled or waved by means of my improved curling stick without necessitating the performance of the waving operation on that portion of the strand which had been previously waved or curled. Further, it will be observed that by the use of my improved curling stick any desired portion of a strand of hair may be waved without subjecting the remaining portion thereof to the same operation.

It will also be noted that the slit 14 provided with the curved outer ends 15 affording communication between the end of the tube 10 and the opening 16 will permit the easy and ready insertion of the free end of the strand 20 into the tube 10 where it will be disposed out of contact with the outer surface of said tube.

It is believed that my invention, its mode of construction and many of its advantages should be readily understood from the foregoing without further description, and should also be manifest that while a preferred embodiment of the invention has been shown and described for illustrative purposes the structural details are nevertheless, capable of wide variation within the purview of my invention as defined in the appended claims.

What I claim and desire to secure by Letters Patent of the United States is:—

1. A hair curling stick of the character described, comprising a tubular body having a concave cylindrical surface and open at one

end, said body having a longitudinal slit provided on the periphery thereof, said slit being in communication with the open end of said body whereby a portion of a strand of hair may be disposed within the hollow body through its open end and the remaining portion of said strand extend through said longitudinal slit to permit it to be wound on said stick.

2. A hair curling stick of the character described, comprising a tubular member of circular cross section throughout, of least outside diameter at the middle thereof and of greatest outside diameter near the ends thereof, and provided with an open end and having on the periphery thereof a longitudinally disposed opening in communication with said open end whereby a strand of hair may be clamped intermediate the ends thereof and that portion of the strand lying on one side of said clamping means be disposed within said hollow body through the open end thereof, and the remaining portion of said strand be permitted to extend in a flatwise condition through said longitudinal opening to permit the same to be wound on said stick.

3. A hair curling stick of the character described, comprising a middle section hollow throughout its length having a concave cylindrical surface and open at one end, said middle section being adapted to have a portion of a strand of hair wound thereabout, the outer periphery of said middle section being provided with a longitudinal opening which is in communication with said open end whereby a portion of the said strand of hair may be inserted through the said open end for disposition within the said hollow middle section, the remaining portion of said strand being adapted to extend in a flatwise condition through the said longitudinal opening in position to be wound upon said middle section.

4. In a hair curling stick, a middle hollow section of circular cross section throughout, of least outside diameter at the middle thereof, and of greatest outside diameter near the ends thereof, and open at one end and adapted to have a strand of hair wound thereabout, the said section having a longitudinal opening provided on the outer periphery thereof, means for clamping said strand of hair at a point intermediate the ends thereof, the portion of said strand of hair lying on one side of said clamping means, together with said clamping means being adapted to disposition within said hollow section through the open end thereof, and the remaining portion of said strand of hair extending through said longitudinal opening in a substantially flatwise condition and being arranged in position to be wound on said middle section for curling the same.

5. In a hair curling stick, a middle hollow section having a concave cylindrical surface,

and open at one end and adapted to have a portion of a strand of hair wound thereabout, means for clamping said strand of hair at a point intermediate the ends thereof, that portion of the strand of hair received between said clamping means being adapted for disposition within said hollow middle section through the open end thereof, the portion of the strand of hair lying on one side of said clamping means extending through said open end and being free to be moved away from said curling stick, and the portion of the strand of hair extending on the other side of said clamping means being adapted to extend through said longitudinal opening to be arranged in a flatwise condition in position to be wound on said middle section in uniform concentric turns for providing a uniform wave therein.

20 In testimony whereof, I affix my signature.
JOSEPH C. BROOKES.
